(57) **CLAIM**

The ornamental design for camera holder, as shown and described.

DESCRIPTION

FIG. 1 is a front, bottom perspective view of a camera holder showing my new design;

FIG. 2 is a front view thereof;

FIG. 3 is a rear view thereof;

FIG. 4 is a left view thereof;

FIG. 5 is a right view thereof;

FIG. 6 is a bottom view thereof;

FIG. 7 is a top view thereof; and,

FIG. 8 is another perspective view thereof showing an open state of use.

The broken lines shown on the drawings depict portions of the camera holder that form no part of the claimed design.
